UNITED STATES PATENT OFFICE.

ADOLPH LANG AND HARPER F. SMITH, OF PHILADELPHIA, PENNSYLVANIA, ASSIGNORS OF ONE-THIRD TO CHARLES H. ZINK, OF PHILADELPHIA, PENNSYLVANIA.

APPARATUS FOR PRODUCING HYDRO-OXYGEN GAS.

No. 833,399.

Specification of Letters Patent.

Patented Oct. 16, 1906.

Application filed October 23, 1905. Serial No. 283,879.

To all whom it may concern:

Be it known that we, ADOLPH LANG and HARPER F. SMITH, citizens of the United States, residing in the city and county of Philadelphia, State of Pennsylvania, have invented a new and useful Apparatus for Producing Gas, of which the following is a specification.

In a pending application filed October 10, 1905, Serial No. 282,119, we have described and claimed a novel construction of a lamp in which the air and gas are separately heated by the heat radiating from the mantles in the lamp.

Our present invention consists of a novel construction of an apparatus adapted to produce a gas by employing a system of burners for separately and positively heating the air and gas chambers, said burners being fed by the gas thus formed.

It further consists of novel means for controlling the admission of the air to the air-chamber.

It further consists of novel means for imparting to the air-supply and to the air-chamber a constant and even pressure.

It further consists of novel means for controlling the supply of air and gas to the air and gas heating chambers and novel means for controlling the heating-burners for said chambers.

It further consists of a novel construction and combination of parts in which the heating-burners are so placed that the air and gas chambers are within the heated zone of said burners.

It further consists of a novel construction and arrangement in which the separate air and gas chambers are placed either parallel with the burners or angularly inclined thereto.

It further consists of a novel construction and combination of a chamber in which a union takes place, separate air and gas heating chambers and heating-burners adapted to be fed by the gas formed and to heat said air and gas chambers, and a valved conduit for leading the gas thus produced to a desired point of consumption.

Figure 1 represents a diagrammatical view, partly broken away, of an apparatus for producing gas embodying our invention.

Fig. 2 represents a front elevation, partly in section, of a modified form which may be em-

ployed. Fig. 3 represents a side elevation of Fig. 2. Fig. 4 represents a front elevation, partly in section, of another modification of our invention.

Similar numerals of reference indicate corresponding parts in the figures.

Referring to the drawings, 1 designates a motor of any convenient or conventional type, which is adapted to actuate the air-compressor 2.

3 designates a pipe leading from the air-compressor 2 and provided with a controlling-valve 4, said pipe 3 discharging into an air-chamber 5, which in the present instance we have shown as being constructed in the form of a coiled pipe, said air-chamber being in suitable connection with the chamber 6, which is connected with a chamber 7, which forms a continuation of the chamber 6.

8 designates an intake-pipe for the gas, provided with a suitable controlling-valve 9, said pipe being connected with a gas-chamber 10, which in the present instance is shown in the form of a coil, this pipe being in suitable connection with the chamber 6.

12 designates pipes or conduits leading from the chamber 7, provided with suitable controlling-valves 13 and having supported at their outer ends heating-burners 14.

15 designates a pipe leading from the chamber 7 and provided with a suitable controlling-valve 16 and having a pipe or connection 17 leading from said valve. This pipe or conduit 17 may be led to any desired point of utilization, and in the present instance we have shown this pipe as being in suitable connection with different forms of lighting devices. In the modification shown in Figs. 2 and 3 we have illustrated a different combination of the component parts in which in the present instance we have shown but a single burner 18, although it will be evident that a series of burners may be employed, if so desired.

19 designates an intake-pipe for the gas which communicates with the gas-chamber 20, said chamber being provided with an outlet 21, which connects with the chamber 22, which latter is in communication with the chamber 23, which forms a continuation of the chamber 22.

24 designates an intake-pipe for the air which communicates with the air-chamber

25, which latter is provided with a discharge port or nozzle 26, which opens into the chamber 22 and which in the present instance is centrally located therein and slightly in advance of the gas-discharge port 21.

27 designates a pipe or conduit leading from the chamber 23 to the burner 18.

28 designates a pipe having a valve 29, said pipe leading from the chamber 22 to a desired point where the new gas is to be utilized. It will be apparent that while we have shown only a side elevation of the gas-pipes forming the gas-heating chamber the air-pipes forming the air-heating chamber will be of a similar construction.

In the embodiment shown in Fig. 4 we have shown the pipes as being placed directly above the burners in a horizontal position and parallel therewith, although it will be apparent that in the broad scope of our invention it is immaterial whether the air and gas heating chambers are parallel with the burners or at an angle thereto. In this embodiment, 30 designates the gas-intake pipe which is in suitable connection with the gas-heating chamber 31, which in the present instance we have shown as consisting of three pipes suitably connected, although it will be evident that the number of pipes employed or 35 their distance apart may be varied according to the conditions and requirements.

32 designates a connection leading from the gas-heating chamber to the outlet 33, which is in communication with the chamber 34, said chamber being provided with a second chamber 35, connected therewith, which forms a continuation of the chamber 34.

36 designates an intake-pipe for the air which is in suitable communication with the air-heating chamber 37, which latter is formed of pipes similar to the pipes which form the gas-heating chamber 31.

38 designates a connection leading from the air-heating chamber to the discharge port or nozzle 39, which is slightly in advance of the gas-discharge port 33 and is in communication with the chamber 34. In the present instance we have shown this discharge port or nozzle as being located at one 45 end of the chamber 34 and located substantially centrally therein, although it will be evident that the connections leading from the air and gas heating chambers may be joined with the chamber 34 at any desired 50 point and still be within the scope of our invention.

40 designates a pipe leading from the chamber 35 to the heating-burner 41, through which the gas passes to feed said burners, the flow of gas thereto being suitably controlled by means of valves 42 in the pipes 40.

43 designates a pipe leading from the chamber 35 to a desired point. It will of course be understood that in the embodiment shown

in Figs. 2, 3, and 4 the intake-pipes for the air and gas may be suitably valved, as desired.

The operation will be readily apparent and is as follows: The valve 9 in the intake-pipe 8 is actuated so that the gas will pass through the chamber 10, and when the valves 13 in the pipes 12 are open the heating-burners 14 may be ignited. Simultaneously with the opening of these valves the controlling-valve 4 for the air will be actuated so that the air under any desired pressure is admitted to the air-heating chamber 5. The air and gas heating chambers are separately heated, and the heated air and heated gas coming in contact with each other in the chamber 6 unite to form a gas, it being understood that this gas is instantly formed when these two heated gases come in contact with each other. The new and distinct gas thus formed may be led from the chamber 7 to the valve-pipe 15 to any desired point of utilization.

We are enabled to produce this new gas at a distance from the heating-pipes, because the cooling of the gas in its course through the pipes or conduits after leaving the chamber in which it unites does not depreciate in any essential degree in its previous heating properties nor does it detract from the quality of the illumination. We have found in practice that the reason for this is that after the affinity of the gas takes place these gases become fixed in the form of a distinct gas and cannot then become separated. Because of this fact the chamber in which the gases unite and the air and heating chambers may be situated or seated in any position which is favorable to the affinity of the two heating-gases. We have shown the different pipes as being supplied with suitable controlling-valves in order that the operation may be varied as desired.

It will be apparent that in our novel construction if the burner which is adapted to heat the air-chamber is shut off the air under pressure will unite in the oxidizing-chamber with the heated gas, which produces a gas which gives a better result than the gas ordinarily used for incandescent lighting. We have found in practice, however, that it is preferable to separately heat both the air and the gas, because by heating the atmospheric air or air under pressure and the hydrocarbon gas simultaneously an affinitive relation immediately takes place between the heated gases when they come in contact with each other, because the greatest amount of oxygen from the air is absorbed by the hydrocarbon gas when the gases are thus heated. It will also be seen that in our novel construction the air and gas may be fed to the burners or points of supply in a normal condition, if desired. It will of course be evident that the port leading from the air-heating chamber 5 to the chamber 6 in Fig. 1 would preferably

be constructed in a similar manner to the modifications shown in Figs. 2 and 4 and that this port would also be slightly in advance of the port through which the gas 5 passes from the gas-heating chamber 10 to the chamber 6.

We are aware that it has heretofore been proposed to mix the gas in its normal condition with air in its normal condition and 10 then heat the mixture. We are further aware that it has been proposed to heat the air before it enters and mixes with the gas and, further, that it has been proposed to partially heat the gas and then mix therewith 15 air in its normal condition. In all of these constructions a mechanical mixture is obtained. In so far as we are aware there has not been disclosed in the prior art a construction in which air and gas are separately 20 heated to such a degree that when they are brought into contact in a separate chamber they will unite to form a gas such as is shown and described in our present construction.

We are also aware that it has heretofore 25 been proposed to partially heat the gas and the air; but in all the constructions with which we are familiar the air and the gas have not been separately heated to such a degree that any union of the two partially-heated products would take place owing to the loss of heat by radiation and the omission of a separate chamber into which they discharge and unite. After the gas is once 30 formed it can be led to a desired point of utilization and substantially the same result is obtained when the gas is cooled as when it is utilized in its heated condition. We do not, however, desire to be limited to a construction in which the air-discharge port is in 35 advance of the gas-discharge port, since it will be evident that the gas-discharge port may be in advance of the air-discharge port or adjacent thereto and still be within the scope of our invention, as is clearly illustrated and described in a pending application for method of producing gas filed November 22, 1905, Serial No. 288,599.

Having thus described our invention, what we claim as new, and desire to secure by Letters Patent, is—

1. In a device of the character described, an air-chamber, means for superheating said chamber, a second chamber connected with said air-chamber and located beyond the 55 heat zone of said air-chamber-heating means and means for leading a heated gas to the heated air in said second chamber.

2. In a device of the character described, a chamber, burners connected therewith, separate air and gas chambers superheated by said burners and discharging into said first-named chamber, said first-named chamber being located beyond the heat zone of said burners and means for conveying the gas

formed by the uniting of the heated air and 65 gas to a desired point.

3. In a device of the character described, a chamber, burners connected therewith, separate air and gas chambers superheated by said burners and discharging into said first-named chamber, said first-named chamber being located beyond the heat zone of said 70 burners, means for conveying the gas formed by the uniting of the heated air and gas to a desired point and separate means for controlling the flow of air and gas to said air and gas chambers.

4. In a device of the character described, a chamber, heating-burners fed by the gas from said chamber, separate air and gas 80 chambers heated by said burners and discharging into said first-named chamber, said first-named chamber being located beyond the heat zone of said burners, means for controlling the entrance of air and gas to said air and 85 gas chambers, and means for compressing the air supplied to said air-chamber.

5. In a device of the character described, an air-chamber, means for conveying air under pressure thereto, a second chamber connected with said air-chamber, burners fed by said second chamber and superheating said air-chamber, said second chamber being located beyond the heat zone of said burners, means for leading heated gas to said second 95 chamber and a conduit leading from the latter to a desired point.

6. In a device of the character described, an air-chamber, means for conveying air under pressure thereto, a gas-chamber in suitable connection with a gas-supply, means for separately superheating said chambers, means for uniting the heated products to form a gas, said last-named means being beyond the heat zone of the chamber-heating 105 means and means for leading said gas to a desired point.

7. In a device of the character described, a chamber, heating-burners, connection between said burners and said chamber, separate air and gas chambers within the heat zone of said burners and connected with said first-named chamber, said first-named chamber being located beyond the heat zone of said 110 burners, separate means for controlling the flow of air and gas to their respective chambers and means for conveying the new gas to a desired point.

8. In a device of the character described, a chamber, heating-burners, connections between said burners and said chamber, separate air and gas chambers within the heat zone of said burners and connected with said first-named chamber, said first-named chamber being located beyond the heat zone of 125 said burners, separate means for controlling the flow of air and gas to their respective chambers, means for conveying the new gas

to a desired point and means for compressing the air-supply to said air-chamber.

9. In a device of the character described, separate air and gas chambers, heating devices for expanding the air and gas in said chambers, means for maintaining under a constant pressure the air entering said air-chamber, a third chamber connected with said chambers and in which the expanded air and gas unite to form a separate new gas and means for leading said gas to a desired point.

10. In a device of the character described, separate air and gas chambers, a third chamber, connections between the latter and said air and gas chambers, heating-burners, connections between said burners and said third chamber, said third chamber being located beyond the heat zone of said burners, separate means for controlling the flow of air and gas to their chambers and a valve-conduit leading from said third chamber to a desired point.

11. In a device of the character described, a chamber, separate air and gas chambers connected therewith, means for superheating either of said air and gas chambers as desired, said first-named chamber being located beyond said heating means and a

valve-conduit leading from said first-named chamber.

12. In a device of the character described, a chamber, separate air and gas chambers connected therewith, heating-burners for said air and gas chambers, valve connections between said burners and said first-named chamber and said first-named chamber being located beyond the heat zone of said burners and separate means for controlling the admission of air and gas to their respective chambers.

13. In a device of the character described, a chamber, an air-chamber connected therewith, a gas-chamber connected with said first-named chamber, means for leading air under pressure to said air-chamber, means for controlling the supply of gas to said gas-chamber, means for superheating said air and gas chambers, said first-named chamber being located beyond said heating means and a conduit leading from said first-named chamber to a desired point of utilization.
